United States Patent Office

Des. 201,883
Patented Aug. 10, 1965

201,883

CAN OPENER

Casimir F. Gruska, Chicago, Ill., assignor to Ekco Products Company, Chicago, Ill., a corporation of Delaware

Filed Oct. 13, 1964, Ser. No. 82,151

Term of patent 14 years

(Cl. D22—2)

FIG. 1

FIG. 5

FIG. 2

FIG. 3

FIG. 4

FIG. 1 is a side elevational view of a can opener showing my new design.

FIG. 2 is a top plan view thereof.

FIG. 3 is a side elevational view taken from the side thereof opposite to that appearing in FIG. 1.

FIG. 4 is a front end elevational view thereof.

FIG. 5 is a vertical section taken along line 5—5 of FIG. 1.

I claim:

The ornamental design for a can opener, as shown.
